(57) **CLAIM**

The ornamental design for a three-wheeled velocipede without pedals, as shown and described.

DESCRIPTION

FIG. 1 is a front and right side perspective view from above, of a three-wheeled velocipede without pedals, constructed according to my new design, the front left side being substantially the mirror image thereof with the exception of the small protruding structure located on the main frame portion which receives the T-bar;

FIG. 2 is a front view thereof;

FIG. 3 is a right side elevational view thereof; the left side elevational view being substantially the mirror image thereof, with the exception of the small protruding structure located on the main frame portion which receives the T-bar;

FIG. 4 is a rear view thereof;

FIG. 5 is a top plan view thereof; and,

FIG. 6 is a bottom plan view thereof.
